UNITED STATES PATENT OFFICE.

CHARLES R. FRENCH, OF NEWARK, NEW JERSEY.

RADIOFREQUENCY TRANSFORMER.

Application filed June 18, 1925. Serial No. 38,016.

This invention relates to improvements in constructions of radio frequency transformers and particularly to a transformer of this type adapted for use in conjunction 5 with radio receiving sets.

An object of the invention resides in providing a radio frequency transformer for radio sets adapted to provide an air core and suitable supports for the primary and 10 secondary windings which are preferably constructed in a predetermined manner in order to provide a low loss structure.

Another object of the invention resides in providing a mounting for the primary and 15 secondary windings of the transformer construction wherein suitable supporting elements are provided for the secondary which are mounted in spaced relation in a predetermined manner and held by suitable spacing 20 means which supports the primary winding, and wherein a suitable housing is formed of separable parts which receives the coil supporting structure and through a single securing means mounts the parts 25 of the housing and the coiled structure in assembled relation.

The invention also comprehends other objects and improvements in the details of construction and arrangement of parts which 30 are more particularly pointed out in the following detailed description directed to a preferred form of the invention, it being understood however, that various changes in the size, shape and arrangement of the parts 35 may be made in order to adapt the construction to supporting the primary and secondary windings in different predetermined relation without departing from the spirit or scope of the invention as herein set forth.

40 In the drawings forming part of this application:

Figure 1 is a vertical transverse sectional view through the assembled transformer.

Fig. 2 is a longitudinal sectional view 45 on a plane passing through the axis of the coil indicated by the line 2-2 in Fig. 1.

Fig. 3 is an enlarged plan view of a section of the coil supporting structure showing the manner of mounting and spacing 50 the windings of a lattice wound secondary coil.

Fig. 4 is an end elevation of the housing containing the coils.

The coil supporting structure includes a 55 plurality of flat annular ring members 1 preferably formed of suitable insulating ma-

terial, the outer peripheries of which are provided with a series of substantially equally spaced notches 2 in which the wires forming one of the coils are adapted to pass. 60 These annular plates 1 are adapted for mounting in spaced parallel relation as shown in Figs. 1, 2 and 3, and are retained in this position by suitable spacing members 4 of sleeve-like form and constructed 65 of suitable insulating material. The sleeves 4 between each adjacent ring 1 are mounted in alined relation at spaced intervals throughout the circumference of the ring members and receive holding rods 5 which 70 extend therethrough and through suitable openings in the rings 1 and serve to retain the rings and sleeves in proper assembled spaced relation. The ends of the rods 5 extend beyond the ends of the sleeves 75 and the rings and receive short spacing sleeves 6 terminating short of the ends of the rods for spacing the end plates or disks 7 of the housing from the ends of the coils and the end ring members. The projecting ends of the rods 5 are received within 80 suitable sockets 8 in the end plates, which rods and spacing sleeves form the means for determining the position of the end disks 7 in the assembled relation of the parts. A 85 cylindrical casing 9 is received within the rabbeted edge of the end disk and cooperates therewith to form a dust tight housing for the coil mounting structure.

A bar 10 extends through the central portion of the housing and openings in the disk 7 and is threaded at the ends to receive nuts 11 which when tightened against the disks serve to lock the parts in assembled relation. 95

The spacing sleeves 4 are provided with annular grooves 12 in substantially equally spaced relation on the peripheries thereof and which are adapted to receive the coil windings of the primary coil 13. The primary coil winding as disclosed in the drawing particularly in Figs. 1 and 2, is a helical winding in which the adjacent convolutions are mounted in spaced relation as illustrated. The ends of these windings are secured to suitable binding posts 14 mounted on the end disk 7 so that the coil may be interposed in the proper manner in a radio receiving circuit. The ring members 1 form 100 the supports for the special form of secondary winding used in this transformer which is termed in the art as the lattice type 105 110

of winding. The coil convolutions of the secondary winding indicated by the numeral 13 extend diagonally from one end of the coil to the other and the successive diagonal portions of each coil convolution are in spaced relation with respect to the adjacent coil convolutions, the wires extending through the notches 2 in the rings so that the rings form a supporting and spacing means for the lattice winding of the coils of the secondary. The ends of the secondary windings are secured to other of the binding posts 14 mounted on the end disk 7 so that this coil may be also properly interposed in a radio receiving circuit.

From this construction, it should be readily understood that all convolutions of both of the coils are insulated by air spaces and each of the coils insulated from one another by air spacing in addition to providing an air core therefor. It will be seen that the construction of the rings 1 with the notches 2 therein form a means for mounting and permitting the efficient winding of the lattice coils and at the same time properly spacing the adjacent strands of the coil at a plurality of points intermediate the ends thereof in order that a most efficient construction of lattice coil will be provided for efficient cooperation with the primary wound in helical form on the sleeves 4 and in which the wires are seated in the grooves of the sleeves so that they are retained in proper spaced relation, while the sleeves at the same time form proper spacing means for the rings 1.

In addition particular attention is called to the fact that the cylindrical housing member 9 removably receives the assembled coil structure on the rings 1 and that the end plates 7 form a locking means to prevent the removal of the rods 5 and the disassembling of the coil structure which are all held in assembled relation by a single holding means, namely, the rod 10 threadedly receiving the nuts 11 cooperating with the end disks 7 of the casing.

What is claimed as new is:—

1. A transformer, comprising a coil supporting structure having a plurality of annular coil supporting members mounting one coil winding, spacing and holding means for positioning said members in predetermined spaced relation, a second coil mounted by said means, a sectional housing for said coil supporting structure removably mounting said means, and securing means for holding the housing in assembled relation.

2. A transformer, comprising a coil supporting structure having a plurality of annular coil supporting members, spacing members for said coil supporting members, holding means mounting said spacing means and coil supporting members, one coil winding supported by said supporting members, another coil winding supported by said spacing members, a sectional housing for said coil supporting structure having removable engagement with said holding means, and securing means for holding the sections of a housing and the coil supporting structure in assembled relation.

3. A transformer, comprising a coil supporting structure having a plurality of ring members, spacing members for said ring members, holding means engaging said spacing members and ring members adapted to hold said ring members in predetermined spaced relation, one coil supported by said ring members, and other coil windings supported by said spacing members, a cylindrical housing section for receiving said coil supporting structure, a pair of end plates for cooperation with said cylindrical housing section to form a closed container for said coil supporting structure, said end plates mounting said holding means, and assembling means engaging said end plates for retaining said housing and coil supporting structure in assembled relation.

4. A transformer, comprising a coil supporting structure including a plurality of annular plate members, said plate members being arranged in axially aligned relation, a plurality of spacing members arranged in circumferential relation between said annular plate members, a plurality of holding rods extending through said spacing members and plate member for retaining said members in assembled relation, a primary coil winding mounted on said spacing members, a secondary coil winding mounted in spaced circumferential relation on said plate members, a cylindrical housing section receiving said coil supporting structure, a pair of end plates removably engaging the ends of said housing section, said end plates being formed with sockets receiving said holding member, and securing means for retaining said end plates in engagement with said housing section adapted to retain said coil supporting structure in assembled relation and completely enclosed within said housing.

In testimony whereof I affix my signature.

CHARLES R. FRENCH.
